(57) **CLAIM**

The ornamental design for a tibial depth resection stylus, as shown and described.

DESCRIPTION

FIG. 1 is a perspective view of a tibial depth resection stylus shown in an environment illustrating our new design; FIG. 2 is a front end elevation view of the tibial depth resection stylus shown removed from its environment in order to show aspects of the design that are not apparent in the perspective view;

FIG. 3 is a rear end elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof.

The broken lines shown that are immediately adjacent the shaded areas represent unclaimed boundaries while the dot-dash broken lines are directed to environment and are for illustrative purposes only; the broken lines form no part of the claimed design.
